UNITED STATES PATENT OFFICE.

OTTO C. SCHWARZ, OF NEW CHICAGO, INDIANA.

BUILDING-BLOCKS FOR TOY CASTLES.

1,061,637.

Specification of Letters Patent.

Patented May 13, 1913.

Application filed April 25, 1912. Serial No. 693,147.

To all whom it may concern:

Be it known that I, OTTO C. SCHWARZ, a citizen of the United States, and a resident of New Chicago, in the county of Lake and 5 State of Indiana, have invented certain new and useful Improvements in Building-Blocks for Toy Castles; and I do hereby declare that the following is a full, clear, and exact description thereof, reference being 10 had to the accompanying drawings, and to the characters of reference marked thereon, which form a part of this specification.

This invention relates to a series of novel building blocks, so constructed and arranged 15 as to be capable of being placed together to represent a feudal castle, a building, a bridge or other structure, and the invention consists in the construction, arrangement and combination of the parts hereinafter 20 described and more particularly pointed out in the appended claims.

The purpose of the invention is to provide a novel construction of blocks of this character so arranged that they may be assembled 25 to produce a structure of massive and pleasing effect and of various contours and outlines, with the individual parts thereof so constructed that they may be packed for shipment or storage in small compass when 30 disassembled.

In the drawings;—Figure 1 is a perspective view of a toy castle embodying my invention. Fig. 2 is a perspective view of one 35 of the larger towers. Fig. 3 is detail vertical section thereof. Fig. 4 is a transverse section of the tower. Fig. 5 is an inverted perspective view of the top piece or cornice of the tower. Fig. 6 is a perspective view of a unit or section of the wall. Fig. 7 is a side 40 elevation of one half of the gate-way piece or unit. Fig. 8 is a horizontal section, indicated on the line 8—8 of Fig. 7. Fig. 9 is a perspective view of one of the parts of the 45 sectional base of the tower. Fig. 10 is a perspective view of one of the members of the multi-part column base.

In the drawings I have shown one form of structure in which my invention can be embodied, to wit, a feudal castle but it will be 50 understood that the same may be embodied in other structures, as for instance, buildings, bridges and the like and that certain of the architectural contours will be varied in the different embodiments of the invention.

The wall of the castle or inclosure com-

prises as its salient parts the towers 10 and 11 (the latter shown as constituting corner towers and made of less height than the former, which occupies a middle portion of 60 the wall), wall units 12 and 13, wall and corner posts 14, 15, (the former being arranged principally in the line of the wall and the inner angles of the walls, and the latter at the outer angles or corners of the 65 walls) and a gate-way piece or unit 16 having an arched way therethrough.

The tower 10 is shown in detail in Figs. 2 and 5, both inclusive. It is herein shown as made of rectangular cross section, and comprises four panels 18, 18, made of thin stock, preferably of cross-grained veneer, four corner posts 19, 19, a top piece 20 and a base designated as a whole by 21. Each corner post 19 is longitudinally grooved on two of 75 its adjacent sides to receive the side margins of the panels 18, as indicated in Fig. 4; said panels fitting in said grooves with a fairly loose fit to hold them in assembled relation while permitting the parts to be 80 readily assembled and dismounted. While the cross section of the tower is shown as rectangular, it may assume other cross sections, as for instance, circular. The top piece 20 comprises an open frame consisting 85 of members 22, 22 and a horizontal plate or member 23, the whole being glued or otherwise rigidly fastened together. The exterior and top portions of the members of the top piece may be treated to produce any conventional or desired architectural contour. The side members 22 of the top piece are recessed or cut away at their corners, as indicated at 24, to constitute notches to set 90 down over the corner posts 19 of the tower 95 to thus produce an interlocking connection between the top piece and the posts and panels. The panels fit at their tops within the side faces of the thickened portions of the side members 22 of the top piece. The 100 interlocking connection of the top piece with the corner posts and panels, as described, strengthens the tower, as a whole, so as to enable it to be readily handled, as a unit without danger of collapsing.

The base 21 of the tower may be made in a manner generally similar to the top piece 20. I prefer, however, to make said base of a plurality of sections 25, 25 and 26. The shape of the former is shown in Fig. 9, it 110 comprising a narrow solid portion having at one side the flange 27 and at its end the

flanges 28, 28. The flanges 27 are recessed at 29 to constitute recesses to interlock the base member with the corner posts 19 of the tower. The intermediate members 26 extend 5 across the base of the tower and are provided at their ends with the upturned flanges 30 to overlap the lower ends of the tower panels, as shown in Figs. 3 and 4.

The corner towers 11 are made like the 10 larger or central tower 10 with respect to the corner posts, panels and top pieces, all of which bear reference numerals similar to the larger tower. Preferably however, the corner towers are not provided with bases, but 15 rest with their posts and panels directly on the supporting surface.

The wall sections or units 12, one of which is shown in Fig. 6, each comprise a panel 32, a wide base 33 and a narrower top piece 34. The said base is grooved at its upper 20 side or margin, and the top piece is grooved at its lower side or margin to receive the lower and upper marginal portions, respectively, of the panel 32, the said panel margins fitting sufficiently tight in the base and 25 top piece grooves to retain the parts in assembled relation, while permitting them to be readily dismembered. It will be observed that the terminal pieces, bases and top pieces 33, 34, are disconnected, except for the panels 32, the latter constituting the sole connection between the terminal pieces.

The gate-way piece or unit 16 comprises a wide panel 35 provided with an arched 35 opening 36, two bases 37, 37 at the sides of said opening, which are grooved at their upper side margins to receive the lower margins of the legs of the panel 35, and the top piece 38 which is also grooved on its under 40 side to engage over the top margin of the panel 35. The said top piece 38 may be finished according to a conventional or preferred architectural design, it being herein shown as of general triangular cross section, 45 with its base grooved to fit over the panel 35. Between the bases 37 and the top piece 38 of the gate-way section or unit the side margins of the gate-way panel 35 are inclosed by the grooved finishing strip 39 which gives 50 a finished appearance to the sides of the panels and to the joint between the gate-way piece panel and the adjacent side wall unit or section. The corner posts 15 may likewise be surmounted by top pieces 40 which are 55 grooved on their under sides to receive the tongues 41 in which said corner posts terminate at their upper ends.

The wall sections 13 are of lattice or open-work construction, comprising horizontal 60 and vertical cross bars 43, 44, the latter of which are arranged between and separate the cross bars 43 so as to allow them to fit over the panels 32 of adjacent wall sections as shown in Fig. 1.

65 In Fig. 1 is shown one form of castle

which may be made of the blocks or units heretofore described, and from an inspection thereof, and of the several pieces illustrated, it will be apparent that such form may be widely varied to produce different 70 architectural effects and designs of castles from the same set of blocks or pieces.

The purpose of making the base 21 of the tower 10 of sectional form is to permit one of the sections of the base to be removed, as 75 indicated in Fig. 2, so that the base 33 of an adjacent wall section or unit may be set slightly into the base line of the tower so as to bring the margin of the panel 32 of the wall section or unit flush with the side face 80 of the adjacent panel of the tower.

If desired, one of the wall panels of the tower may be provided with a hinged section 45 which is adapted to swing downwardly and outwardly about pivots 46, and, 85 when swung upwardly, to close an opening 47 in said panel. The said swinging section may be supported in its downward position by the chains 48 which are attached to the outer ends of said swinging section and are 90 trained through openings 49 in an inset piece 50 at the top of said opening. Said chains are connected at their inner ends, within the tower, with a weight 51 which serves, when the hinged portion is swung upwardly, to 95 hold the same in its closed position. The parts just described produce the effect of a draw-bridge. Stops 52 extending across the outer side of the swinging draw-bridge section limit the closing movement thereof. 100

The bases and top pieces of the towers and wall sections or units, as well as the exposed sides of the tower, corner posts and finishing strips of the gate-way unit may be treated with an exterior finish or coating of a sand 105 or stone mixture to give a stone or concrete finish thereto, or what I term a "granite veneer". The wall and tower panels and the gate-way panels may also have a surface finish of any desired character in imitation of 110 masonry and window openings.

While I have shown my invention as embodied in a castle or fortress structure, it will be obvious that the salient features thereof may be embodied in other structures, 115 as buildings, bridges, etc., and also that the architectural details or contours and the manner of arranging the parts in the structure may be varied without departing from the essential features of the invention. 120

I claim as my invention:—

1. In a toy structure, a tower comprising grooved posts, panels removably fitted at their margins in the grooves of the posts and a top piece surmounting the tower, said top piece comprising a surrounding wall which fits down over the tower walls and provided with recesses to receive the upper ends of the tower posts. 125
2. In a toy structure, a tower provided 130

- with a multi-part base comprising outer opposite members, arranged side by side and interlocking with the walls of the tower, and a separate, removable intermediate member.
- 5 3. In a toy structure, a tower comprising side panels and posts connecting the same, one of said panels being provided with an opening, a draw-bridge section for closing said opening and adapted to swing to a horizontal position, chains for supporting said draw-bridge section in its open position, and a weight within the tower acting on said chains to hold the draw-bridge section in its closed position.
- 10 4. In a toy structure, the combination with a tower comprising connected panels and a base, of a wall section comprising a base, a top piece and an intermediate panel, said tower base having an opening to receive the wall section base to permit the wall section panel to fit flush against the tower panel.
- 15 5. In a toy structure, the combination with a tower comprising connected panels and a multipart base, of a wall section comprising a panel, a base and a top piece, one of the parts of the base being removable to provide a space at the base to permit an adjacent wall section base to fit thereinto, for the purpose set forth.
- 20 6. In a toy structure, a gate-way section or unit comprising a panel having an arched opening formed therethrough and extend-
- ing to the bottom of the panel, bases at the sides of said opening and provided with 35 grooves to releasably receive the lower end margins of the legs of said panel, a top piece removably fitted to the upper margin of said panel and grooved finishing pieces removably fitted to the side margins of said panel between the said bases and top piece.
- 40 7. In a toy structure, the combination with wall sections comprising panels, bases and top pieces, of an open work or latticed wall section comprising laterally separated 45 side pieces adapted to fit in overlapping relation the panels of the adjacent wall sections and intermediate cross pieces fixed to the side pieces.
8. In a toy structure, a wall section or 50 unit comprising two separate terminal pieces provided at their adjacent edges with grooves and a panel co-extensive in width with the length of the terminal pieces and extending between, and releasably engaging 55 at its edges the grooved portions of the terminal pieces and constituting the sole connection between said terminal pieces.

In testimony, that I claim the foregoing as my invention I affix my signature in the 60 presence of two witnesses, this 19th day of April, A. D. 1912.

OTTO C. SCHWARZ.
